MOLD FORMING APPARATUS

Loyal L. Johnston, Zelienople, Pa., assignor to
Herman Pneumatic Machine Company, Pittsburgh, Pa., a corporation of Pennsylvania

Application March 9, 1948, Serial No. 13,771

10 Claims. (Cl. 22—22)

1

This invention relates to mold forming apparatus and particularly to apparatus for forming molds of molding material such as sand, graphite and the like used in foundries. The invention has to do particularly with the formation of hollow molds and the compacting and shaping of the mold forming material at the inner surface of the mold.

While my invention is of general utility in the preparation of various types of foundry molds it is well adapted for use in forming hollow, generally cylindrical molds of sand or similar mold forming material such as may be used for the casting of generally cylindrical products, for example, the centrifugal casting of pipe. Purely for purposes of explanation and illustration the invention will be described as embodied in mold forming apparatus for the making of sand molds for the centrifugal casting of cast iron soil pipe. The apparatus which is the subject of the present invention may be embodied in molding machines of the type disclosed in my copending application Serial No. 643,318, now Patent No. 2,449,900, granted September 21, 1948.

Apparatus for forming a hollow, generally cylindrical sand mold for the centrifugal casting of soil pipe comprises a generally cylindrical hollow flask which may be rotated both during formation of the sand mold and during centrifugal casting of the soil pipe, preferably at relatively high speed during the latter period, the sand mold being formed therein by introducing sand, rotating the flask and introducing into the flask a former or mandrel whose function is to engage and press against the sand to compact and shape the inner surface thereof, i. e., the surface of the mold which is to contact the molten metal during centrifugal casting. In one method of procedure the sand is introduced into the flask and the flask is rotated fast enough to cause the sand to cling to the inner surface of the flask, an axial hole through the sand thereby being formed. The former or mandrel may be introduced through the hole. Desirably a generally cylindrical mandrel is used. During introduction of the mandrel it may be positioned coaxially with the flask and hence coaxially with the hole in the sand. After the mandrel has been introduced its free end is preferably supported so that the mandrel when ready for operation upon the sand is in the nature of a beam supported at both ends outside the flask.

The mandrel supports may be journals in which the mandrel is rotatably mounted. The supports are movable transversely of the axis of the flask

2

so that with the mandrel in position as aforesaid it may be moved as a whole transversely of the axis of the flask to press against the sand therewithin as the flask rotates. The mandrel may be positively rotated or it may be freely mounted to rotate by reason of its frictional contact with the sand.

As the mandrel is moved transversely of the axis of the flask it compacts and shapes the sand to form in the flask a generally cylindrical hollow sand mold with its inner surface smoothed and compacted and which is adapted for the centrifugal casting of cast iron soil pipe. After the mold has been compacted and shaped the mandrel may be returned to substantially coaxial position in the flask and may be withdrawn from the flask, after which the flask may be provided with a core at one end and molten iron may be introduced to form the soil pipe. The present invention has nothing to do with the method employed in the centrifugal casting of the soil pipe and it may be assumed that a conventional centrifugal casting method is employed.

One of the principal problems which has been encountered in the making of soil pipe by centrifugal casting has been that the pipe has not been of uniform outside diameter, the outside of the pipe has not been straight and the wall thickness of the pipe has not been uniform. This has been due to the fact that the inner surface of the sand mold in the flask, i. e., the surface against which the molten metal forming the outside of the pipe freezes during centrifugal casting, has not been straight axially of the flask. Since that surface is formed by the mandrel it follows that at the time of formation the mandrel has not been straight. It has been found that the mandrel for forming the mold is subject to deflection and actually deflects when in use. When a cylindrical mandrel is used which is supported at both ends and that mandrel is pressed against the sand in the flask the mandrel deflects, the middle portion thereof being pushed back by the sand away from the flask. Thus although the mandrel when not in use may be straight it is curved during the time when it is forming the mold. The result is that the inside diameter of the sand mold in which the pipe is cast is smaller at the middle portion of the mold than at the ends. This shape is transmitted to the outside of the pipe and the undesirable results above pointed out occur.

I have devised mold forming apparatus obviating the disadvantages above explained. I provide mold forming apparatus comprising a flask

adapted to contain a hollow body of molding material and a former extending within the flask for compacting and shaping the inner surface of the molding material, the former being subject to deflection when pressed against the molding material and being shaped so that when deflected by being pressed against the molding material the surface thereof in contact with the molding material assumes predetermined desired conformation different from its conformation when undeflected whereby to impart to the molding material a predetermined desired shape. When it is desired to form a cylindrical mold the former is designed with its middle portion which engages the mold bulged outwardly when not under deflection; when the former is in use under deflection its sand engaging surface will be approximately straight and a cylindrical mold will be formed. If it is desired to form a mold which is of other than cylindrical shape the desired shape of the mold is ascertained and the former is designed so that its mold forming surface differs from the desired shape of the mold by the amount which it will deflect when in use.

Other details, objects and advantages of the invention will become apparent as the following description of a present preferred embodiment thereof proceeds.

In the accompanying drawings I have shown a present preferred embodiment of the invention in which

Figure 1 is a diagrammatic axial cross-sectional illustration of a conventional flask and mandrel for the formation of a sand mold for the centrifugal casting of cast iron soil pipe;

Figure 2 is a view similar to Figure 1 but showing my improved mandrel and the improved results obtained by its use; and

Figure 3 is an enlarged view of my improved mandrel but with a portion cut away.

Referring first to Figure 1, there is shown a flask 2 which is of generally cylindrical shape with a generally cylindrical bore 3 therein, the bore being enlarged at one end as indicated at 4 for the formation of a pipe bell. The flask itself may be of conventional design, being desirably of cast iron. Cooperating with the flask to form a mold of sand 5 disposed within the flask is a former or mandrel 6. The mandrel 6 when in use is mounted in bearings 7 and 8 at its respective ends so that it may rotate in contact with the sand. It has an enlargement 9 within the portion 4 of the flask as is conventional. The mandrel also has a spigot forming enlargement 10. Between the enlargements 9 and 10 the mandrel is cylindrical.

The bearings 7 and 8 are mounted so that when the mandrel is in place in the flask they may be moved in unison transversely of the axis of the flask to bring the mandrel into engagement with the sand to compact and shape the sand into a mold. In Figure 1 the direction of movement of the bearings 7 and 8 transversely of the axis of the flask is toward the top of the figure. The mandrel has been moved against the sand at the upper portion of the figure and the pressure of the slender mandrel against the sand has caused it to deflect or bend so that its central portion is disposed farther from the upper inner surface of the flask than its end portions. The bending of the mandrel is indicated in Figure 1. This results in the formation of a sand mold whose internal diameter is substantially less in the region of its middle portion than at its ends. The disadvantages of the for-

mation of such a mold have been explained above.

Figure 2 shows a flask and mandrel made in accordance with my invention. The flask 2 and the bearings 7 and 8 may be the same as in Figure 1. However the mandrel 6' of Figure 2 is different from the mandrel 6 of Figure 1. The enlargements 9' and 10' of the mandrel 6' may be identical with the enlargements 9 and 10 of the mandrel 6 but the portion of the mandrel 6' between the enlargements 9' and 10' is not cylindrical. It is bulged adjacent its center, i. e., the diameter of the mandrel at its center is substantially greater than its diameter adjacent its ends.

The mandrel 6' will deflect when in use but since it is made with its center bulged when not under deflection the surface of the mandrel engaging the sand will be substantially straight when the mandrel is deflected and will result in the formation of a sand mold having a substantially cylindrical inner surface.

While I have shown and described a present preferred embodiment of the invention it is to be distinctly understood that the invention is not limited thereto but may be otherwise variously embodied within the scope of the following claims.

I claim:

30. 1. Mold forming apparatus comprising a flask adapted to contain a hollow body of molding material and a former extending within the flask for compacting and shaping the inner surface of the molding material, the former being of small cross-section in relation to its length and hence being subject to deflection when in use, the mold engaging surface of the former being when undeflected convexly curved in the longitudinal direction so that when under deflection in use the portion of it in engagement with the mold will be substantially straight in the longitudinal direction whereby to form a substantially straight mold.

45. 2. Mold forming apparatus comprising a flask adapted to contain a hollow body of molding material and a former extending within the flask for compacting and shaping the inner surface of the molding material, the former being of small cross-section in relation to its length and hence being subject to deflection when in use, the mold engaging surface of the former being when undeflected bulged outwardly in the region of its middle so that when under deflection in use the portion of it in engagement with the mold will be substantially straightened out whereby to form a substantially straight mold.

60. 3. Mold forming apparatus comprising a rotatable flask adapted to contain a hollow body of molding material and a forming mandrel extending within the flask for compacting and shaping the inner surface of the molding material upon rotation of the flask, the mandrel being of small cross-section in relation to its length and hence being subject to deflection when in use, the mold engaging surface of the mandrel being when undeflected bulged outwardly in the region of its middle so that when under deflection in use the portion of it in engagement with the mold will be substantially straightened out whereby to form a substantially straight mold.

70. 4. Mold forming apparatus comprising a rotatable flask adapted to contain a hollow body of molding material and a forming mandrel extending within the flask for compacting and shaping the inner surface of the molding mate-

rial upon rotation of the flask, the mandrel being of small cross-section in relation to its length and hence being subject to deflection when pressed against the molding material, the mold engaging surface of the mandrel being when undeflected bulged outwardly in the region of its middle so that when pressed against the molding material the portion of it in engagement with the mold will be substantially straightened out whereby to form a substantially straight mold.

5. Mold forming apparatus comprising a flask adapted to contain a hollow body of molding material and a slender elongated flexible former extending within the flask for compacting and shaping the inner surface of the molding material, the former being subject to deflection when pressed against the molding material, the surface of the former which engages the molding material being, when the former is undeflected, of conformation differing from the conformation of the mold to be formed by an amount such that when the former is deflected by pressing it against the molding material in formation of the mold the portion of such surface in engagement with the molding material will assume said conformation of the mold.

6. Mold forming apparatus comprising a rotatable flask adapted to contain a hollow body of molding material and a slender elongated flexible forming mandrel extending within the flask for compacting and shaping the inner surface of the molding material upon rotation of the flask, the mandrel being subject to deflection when pressed against the molding material, the surface of the mandrel which engages the molding material being, when the mandrel is undeflected, of conformation differing from the conformation of the mold to be formed by an amount such that when the mandrel is deflected by pressing it against the molding material in formation of the mold the portion of such surface in engagement with the molding material will assume said conformation of the mold.

7. Mold forming apparatus comprising a rotatable flask of generally circular cross-section adapted to contain a hollow body of molding material and a slender elongated flexible forming mandrel of generally circular cross-section extended through the flask and supported at both ends for movement transversely of its length relatively to the flask to engage, compact and shape the inner surface of the molding material upon rotation of the flask, the mandrel being mounted for rotation while in engagement with the molding material, the surface of the mandrel which engages the molding material being, when the mandrel is undeflected, of conformation differing from the conformation of the mold to be formed by an amount such that when the mandrel is deflected by pressing it against the molding material in formation of the mold the por-

tion of such surface in engagement with the molding material will assume said conformation of the mold.

8. A slender elongated flexible former for compacting and shaping the inner surface of molding material in a flask, the former being subject to deflection when pressed against the molding material, the surface of the former which engages the molding material being, when the former is undeflected, of conformation differing from the conformation of the mold to be formed by an amount such that when the former is deflected by pressing it against the molding material in formation of the mold the portion of such surface in engagement with the molding material will assume said conformation of the mold.

9. A slender elongated flexible rotatable forming mandrel of generally circular cross-section for compacting and shaping the inner surface of molding material in a flask, the mandrel being subject to deflection when pressed against the molding material, the surface of the mandrel which engages the molding material being, when the mandrel is undeflected, bulged outwardly in the region of its middle so that when the mandrel is deflected by pressing it against the molding material in formation of the mold the portion of such surface in engagement with the molding material will be relatively straightened out.

10. Mold forming apparatus comprising a rotatable elongated open-ended flask adapted to contain a hollow body of molding material and forming means extending through the flask and supported at both ends of the flask for compacting and shaping the inner surface of the molding material upon rotation of the flask, said means being of small cross-section in relation to the length thereof and hence being subject to deflection when pressed against the molding material, the transverse dimension of said means in the region of its middle being greater than the transverse dimension of said means adjacent the ends of the flask so that when said means is pressed against the molding material the portion of the surface thereof in contact with the molding material will tend to straighten out.
